POCKET ASH TRAY

Charles H. Schetzer, P.O. Box 441, Goodland, Kans.

Filed May 3, 1965, Ser. No. 85,088

Term of patent 14 years

(Cl. D85—2)

FIG. 1

FIG. 2

FIG. 1 is a perspective view of a pocket ash tray in the closed position, showing my new design, and

FIG. 2 is a similar view showing the same tray in the open position.

The far end and the far side of the tray are respectively similar to the near end and near side shown on the drawing. The bottom of the tray is plain, flat and unadorned.

I claim:

The ornamental design for a pocket ash tray, as shown and described.
